(57) CLAIM

I claim the ornamental design for a hermetically sealed data plug with a tag attachment loop, as shown and described.

DESCRIPTION

FIG. 1 is a bottom perspective view of a hermetically sealed data plug with a tag attachment loop, showing my new design;

FIG. 2 is a top perspective view thereof;

FIG. 3 is a front elevational view thereof;

FIG. 4 is a rear elevational view thereof;

FIG. 5 is a left-side elevational view thereof, the right-side elevational view being a mirror image thereof;

FIG. 6 is a top plan view thereof;

FIG. 7 is a bottom plan view thereof; and,

FIG. 8 is a cross-sectional view thereof, taken along line 8-8 of FIG. 6.

The broken lines showing a first tag in FIG. 1 and a second tag in FIG. 2 depict environmental matter and form no part of the claimed design.
